UNITED STATES PATENT OFFICE.

EDWARD D. CALLEN, OF GREENVILLE, MISSISSIPPI.

EXCAVATOR.

1,342,895.

Specification of Letters Patent.

Patented June 8, 1920.

Application filed September 4, 1918. Serial No. 252,569.

To all whom it may concern:

Be it known that I, EDWARD D. CALLEN, a citizen of the United States, residing at Greenville, in the county of Washington and State of Mississippi, have invented a new and useful Excavator, of which the following is a specification.

This invention relates to excavators and is designed more especially as an improvement upon the structure disclosed in Patent 1,248,262 issued to me on November 27th, 1917.

One of the objects of the invention is to provide simple and efficient means whereby, through the manipulation of cables extending to one end of an area being graded, a conveyer can be moved in one direction to acquire a load by digging it from the ground, can be adjusted to lift the load from the ground, to carry it to a point of discharge, there deliver the load, and return to the place of starting.

A still further object is to provide simple and efficient means for locking the shovel or scraper in lowered or digging position.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings

Figure 1 is a side elevation of the excavator.

Fig. 2 is a plan view thereof.

Fig. 3 is a central vertical longitudinal section.

Fig. 4 is a section on line 4—4, Fig. 3.

Fig. 5 is a section on line 5—5, Fig. 2.

Fig. 6 is a section on line 6—6, Fig. 2.

Fig. 7 is a view of the apparatus in diagram.

Referring to the figures by characters of reference, 1 designates the frame of the excavator which is wider at one end than at the other and extending downwardly from the sides of the broad end of the frame are

guide plates 2 provided with straight slots 3 inclined upwardly toward the broad end of the frame. An axle 4 extends through the slots 3 and is provided, at each end, with a supporting wheel 5, said axle being angular in cross section so as to be held against rotation by the walls of the slots although 60 slideable within the slots. A guide ear 6 extends downwardly from the center of the front or broad end of the frame 1 and slidably mounted therein is a stem 7 one end of which is forked as at 8 and secured to the axle 4, thus to maintain the axle in proper relation to the frame during the movement 70 of the axle longitudinally of the slots.

Pivottally connected to the ears 9 which extend downwardly from the rear lower corners of the plates 2 are the rear ends of the sides of a shovel or scoop 10 which is open 75 at front and back and is limited in its downward movement relative to the frame 1 by chains 11 or the like. Sheaves 12 are mounted on the sides of the scoop close to the front ends thereof and additional sheaves 13 are 80 mounted loosely on the axle 4 close to the wheels 5. A loading cable L has two branches which extend to the respective sides of the frame 1, each branch extending under a sheave, up over a sheave 14 mounted on the 85 side of the frame 1, down under the sheave 13 and thence up the side of the frame 1 where it is secured. Thus it will be seen that when the cable L is pulled its two branches will tend to swing the scoop 10 upwardly relative to the frame. It will also tend to pull through the sheaves 13 upon the 90 axle 4, thereby causing the axle to move forwardly within the slots 3.

A cross bar 15 is secured upon the sides 95 of frame 1 and above the front portion of the scoop 10 and mounted on this bar is a bracket 16 carrying sheaves 17, arranged in pairs as shown, one sheave of each pair being above the other sheave of said pair. 100 The bar 15 also constitutes a stop or abutment for links 18 which are pivotally connected to the sides of the shovel or scoop and are connected, at their upper ends, by a cross rod 19. This rod is engaged by the 105 forward ends of arms 20 extending from the ends of a cross head 21 the ends of which are slidably mounted in guides 22 projecting inwardly from the sides of the frame 1. Upper and lower cross bars 23 connect 110 the sides of frame 1 in front of the cross head 21 and the arms 20 work between them.

Anti-friction rollers 24 are mounted on the rod 19 at the upper ends of the links 18 and are adapted, when the links are in their forward positions, to engage the bottom 5 face of the bar 15.

A guide plate 25 connects the bars 23 and slidably mounted within it is a stem 26 one end of which is secured to the cross head 21 while the other or forward end has head 10 27 engaging one end of a spring 28 which is mounted on the stem and presses backwardly against the plate 25.

The rear end of the frame 1 is supported by a caster 29 and extending inwardly from 15 the sides of the frame close to said end are guides 30. A block 31 is slidably mounted in the guides and is connected to the cross head 21 by parallel upper and lower strips 32 forming slots therebetween. Slidably 20 mounted in these slots are trunnions 33 extending from the forked upper end of an arm 34 which projects upwardly from the end of a beam 35. This beam extends forwardly under the bars 23 and is provided, 25 at its front end, with an ejecting plate which stands on edge upon the bottom of the scoop 10, as shown at 36, and extends from one side to the other of the scoop.

A dog 37 is pivotally mounted in the 30 forked end of the arm 34 and has a head 38 for engaging the block 31. A finger 39 extends radially from the pivot end of the dog and is pivotally connected to a link 40 having a slot 41 through which extends a 35 pin 42. This link and pin co-operate to limit the swinging of the dog 37.

Pivotally mounted on the upper strips 32 at the sides of the dog 37 are latches 43 having heads 44 adapted, under certain 40 conditions, to engage a cross pin 45 connecting the sides of the frame 1. These latches are pivoted between their ends and those ends thereof remote from the heads 44 are extended upwardly and pivotally connected 45 to the forked rear end of a lever 46 fulcrumed in a bracket 47 mounted on the upper strips 32.

The caster 29 has a stem 48 journaled in upper and lower plates 49 secured to the 50 rear end of frame 1 and secured to the stem is a worm wheel 50 in mesh with a worm 51 on a transverse shaft 52. A worm wheel 53 is secured to one end of the shaft 52 and is engaged by a worm 54 at one end 55 of a steering shaft 55. This shaft has a hand wheel 56 whereby it can be operated readily for the purpose of rotating the stem 48 and guiding the device.

In addition to the loading cable L two 60 other cables are employed, namely a rehaul cable R and an unlocking cable U. The rehaul cable R extends from a winding drum or windlass W located at one end of the area being graded and thence between 65 the sheaves 17 of one pair. From these

sheaves the cable passes between sheaves 57 supported in a bracket 58 on the rear end of the frame 1 and thence to another sheave 59 suitably anchored at the other end of the area being graded. From sheave 59 70 the cable R extends back to the conveyer structure, passing over guide sheaves 60 journaled in hangers depending from the rear end of the conveyer, the cable being provided with two branches each engaging 75 one of the sheaves 60, and said branches being indicated at 60'. From its sheave 60, each branch 60' of the rehaul cable extends partly around one of a pair of sheaves 61 mounted in the rear end of the forked 80 portion 8 of stem 7, and from this sheave the branch extends back to one of a pair of sheaves 62 connected to the arm 34 of beam 35. The branch then extends forward and is fastened, as at 63 to one of the 85 plates 2.

The cable U extends from a windlass W and is wound thereon oppositely to the cable R. It passes between the second pair of sheaves 17, over a sheave 64 on the rear portion of the conveyer structure, and thence downwardly into engagement with a sheave 65 on the arm 34, from which it extends upwardly and is secured to the rear portion 90 of the frame 1. A guide sheave 66 may be 95 located on the frame 1 between the sheaves 64 and 65.

The loading cable L is connected to a windlass W' and the windlasses W and W' are adapted to be driven in any suitable 100 manner by an engine E, any suitable arrangement of clutches being employed for controlling the actuation of the windlasses.

The engine and windlasses are to be set up at one end of the area to be graded and 105 the sheave 59 at the other end of said area with the carrier or conveyer arranged between them for travel over the ground. The movement of the device can be controlled by the steering wheel 56.

When the conveyer is at one end of the area at the beginning of the loading operation, the plate 36 is located at the back end of the scoop 10, the dog 37 is engaged with the block 31, the latches 44 are disengaged 115 from the pin 45 and the spring 28 holds the stem 26 pressed forward so that the cross head 21 is in its forward position and the arms 20 hold the links 18 in substantially vertical positions beneath the bar 15. Thus 120 when the loading cable L is pulled by operating the windlass W' it will not elevate the scoop 10 relative to the frame 1 because of the links 18 positioned beneath the bar 15, but it will pull the sheaves 13 and 14 toward each other with the result that the axle 4 will become positioned within the uppermost portions of the slots 3 and the front or digging edge of the scoop 10 thus 125 be forced into the soil. During the con- 130

tinued forward movement of the scoop under the action of the cable L the dirt will pile on the scoop and when the scoop is full the cable U should be pulled. This will cause the cross head 21 to move back and shift the dog 37 out of engagement with the block 31. The latches 44 will at the same time ride on and be elevated by the pin 45 so as to lift lever 46 and the plate 36 will thus be left free to move forward to eject the contents of the shovel or scoop. By maintaining the cable U taut the dog 37 is held up while passing over the block 31. The latches 44 will, by engaging the pin 45, hold the spring 28 under compression. Cable R is of course paid out during the foregoing loading operation and the cable U can at the same time be taken up gradually. This rearward movement of the block 31 not only places spring 28 under compression but also shifts the links 18 from under the bar 15, the latches 44 holding them when so shifted. Further pulling on cable L lifts the sheaves 12, raises the scoop from the ground and allows the carrier to travel freely to the point of delivery. By pulling cable R the plate 36 will eject the material from the scoop and the cable L can then be released and the carrier started on its return movement. When it reaches the point where the scraping or digging is to begin, the carrier is stopped and the lever 46 is shifted to disengage the latches from the pin 45 whereupon the spring 28 will be released and the scoop locked in lowered position relative to the bar 15 and frame 1. Should the spring 28 fail to bring the rollers under the bar 15 the arm 34 would strike cross head 21 and properly set them.

40 What is claimed is:—

1. In an excavator the combination with a wheel supported structure and a scoop movably connected to said structure, of an ejecting plate movably mounted in the scoop, a holding means for fastening the scoop in lowered position relative to the structure, means operated by the movement of the ejecting plate under pressure of dirt collected by the scoop, for releasing the scoop from its holding means, means for fastening the holding means in released position, means for pulling the structure rearwardly, said means being operatively connected to the wheel supported structure and to the ejecting plate, means for automatically locking the ejecting plate against movement to eject the load from the scoop, and means for shift-

ing the ejecting plate to unlock it, said structure pulling means operating to shift the released ejecting plate and eject the load. 60

2. In an excavator the combination with a wheel supported structure and a scoop, of an ejecting plate movable in the scoop, a beam extending from the plate, means for automatically locking the beam and plate against movement to eject the load from the scoop, a loading cable connected to the structure, a haul cable connected to said structure and to the beam for shifting the ejecting plate within the scoop to discharge the load when the beam is unlocked, and means for shifting the beam to unlock it. 70

3. In an excavator the combination with a wheel supported structure, a spring restrained member slidable thereon, and a scoop, of an ejecting plate, a beam extending therefrom, means for automatically locking the beam to the slidable member when the plate is moved in one direction within the scoop, means for shifting the beam and 80 slidable member to unlock the beam, a cable for hauling the structure in one direction, and means upon the beam and structure and engaged by said cable for shifting the ejecting plate to unloading position 85 when unlocked. 75

4. In an excavator the combination with a wheel supported frame and a structure slidable in the frame, of a scoop, an ejecting plate movably mounted in the scoop, a beam 90 extending from the plate and adapted to press against said structure to shift it out of normal position, a latch for holding the said structure in such shifted position, yielding means for returning the structure to normal position when unlatched, means upon the beam for engaging the slidable structure to hold the ejecting plate against movement, a pull cable connected to the excavator for drawing it in one direction to load the 100 scoop, a haul cable for pulling the excavator in the opposite direction, means upon the frame and beam for engaging the haul cable to shift the beam and ejecting plate when the beam is released from the slidable 105 structure, and means for releasing the beam. 95

In testimony that I claim the foregoing as my own, I have hereto affixed my signature in the presence of two witnesses.

EDWARD D. CALLEN.
